UNITED STATES PATENT OFFICE.

CLARENCE W. HAZELETT, OF LAKewood, OHIO, ASSIGNOR TO NATIONAL CARBON COMPANY, INC., A CORPORATION OF NEW YORK.

SEAL FOR STORAGE-BATTERY TERMINALS.

1,380,061.

Specification of Letters Patent. Patented May 31, 1921.

Application filed August 19, 1918, Serial No. 250,600. Renewed March 25, 1921. Serial No. 455,435.

To all whom it may concern:

Be it known that I, CLARENCE W. HAZELETT, a citizen of the United States, residing at Lakewood, in the county of Cuyahoga and State of Ohio, have invented a certain new and useful Improvement in Seals for Storage-Battery Terminals, of which the following is a full, clear, and exact description.

10 This invention relates to a method of sealing storage battery terminals where they pass through the battery covers, and is an improvement on the method disclosed in the patent to Noble and Gossling, No. 15 251,452, Dec. 25, 1917. The details of the method will be described in the following specification and shown in the appended drawings in which:

Figure 1 is a perspective view of a connector strap with the improved terminal.

20 Fig. 2 is a section of a storage battery element and cover with parts in position to form the seal.

Fig. 3 is a section similar to that of Fig. 25 1 with the sealing operation completed.

Fig. 4 is a bottom view of the tool shown in Fig. 2.

Fig. 5 is an elevation of the sealing press with the battery element in position for 30 sealing.

Fig. 6 is a section of a hand sealing tool that may be used to perform the sealing operation.

Fig. 7 is a partial elevation of a modification.

The plate post 1 of the storage battery is molded with an abutment or flange 2 against which the circular boss 4 of the cover 5 is adapted to rest when the element 40 is assembled. The plate post or terminal is molded or otherwise formed with its shouldered portion 6 more or less snugly fitting the hole in the center of the boss 4 of the cover, the top being substantially 45 in line with the top of the boss when the cover is in position. Above the shouldered portion 6 is formed the terminal portion 7 which may be of any desired shape depending upon the particular connector to 50 which it is to be attached.

To apply the seal the cover 5 is inserted over the plate posts 1 and the tool 8 is placed in position over both posts with the cutting edges 9 resting against the shouldered portions 6. Resilient rubber rings 10

encircling the cutting edges 9 hold the cover down while the plate post connection is being riveted in place. The element is then placed over an anvil 11 of the sealing apparatus 12, and air hammer 13 is then caused 60 to operate by depressing the usual lever 14 which rapidly reciprocates the plunger 15 in a well known manner. The reciprocating plunger 15 hits the tool 8 a plurality of blows and this quickly partially severs 65 and then burs over the shouldered portion of the plate post until the lead tightly rivets the cover in place as shown particularly in Fig. 3. After the sealing is completed, lever 14 is released and the element is removed from the sealing press and placed in a battery jar and sealed therein in a manner well known in the art.

While it is the best practice to complete the sealing by means of the air hammer 75 previously described, it is not necessary to use this apparatus. Seals can be completed by means of a tool 16 shown in Fig. 6, which is placed over the plate post in contact with the shouldered portion when the 80 cover is in position. After placing an appropriate support under the plate post the tool is given a sharp blow from a hammer which burs over the lead against the cover and completes the seal of the plate post. 85 The second plate post of the battery is sealed in like manner.

The improved method produces a terminal seal that is exceedingly strong and all leakage of electrolyte is prevented. The flanges 90 2 and the enlargements formed by the partially-severed outwardly-extending portions of the posts limit the movements of the posts in opposite directions in the holes in the cover and securely retain them in place on 95 the cover. The sealing process can be quickly completed with the lead terminal at ordinary temperatures, and no heating of the tool or lead is required. Consequently my improvement reduces the cost of sealing the electrode in place, while producing the same 100 efficient seal disclosed in the patent referred to.

In practice I paint the inside walls of the holes in the cover with any pitch or asphaltum solution, or otherwise form a thin seal between the electrode and the cover so that when the cutting tool rivets the electrode in place all minute inequalities in the surface of the lead or cover are filled with the pitch 110

solution to effectually prevent acid from creeping through the cover.

I may use a resilient gasket 17 of rubber or similar material to prevent the creeping 5 of acid along the lead terminal.

Having described my invention, what I claim is:

1. The process of forming a battery terminal and sealing the same to a battery 10 cover which consists in forming a lead plate post with an enlarged portion and a flange therearound, placing the post in a hole in the cover, and forcing a hollow cutting tool over said post and against said portion to 15 cut the lead and burr it over against the cover.

2. The process of forming a battery terminal and sealing the same to a battery cover, which consists in forming a plate 20 post with an abutment and a shouldered portion, placing the post through a hole in the cover, and forcing a cutting tool against the shouldered portion to bur over the metal against the cover and rivet it in place.

25 3. The method of securing a battery terminal post in a hole in a battery cover, which comprises inserting such post in such hole with a part thereof projecting above the upper side of said cover, cutting into 30 such post to partially sever a portion thereof, and bending such partially-severed portion over against the cover.

4. The method of securing a battery terminal post in a hole in a battery cover, which 35 comprises inserting such post in such hole with a part thereof projecting above the upper side of said cover, cutting into such post to partially sever a portion thereof adjacent the upper side of said cover, and bending 40 such partially-severed portion outwardly and downwardly against such upper side of the cover.

45 5. The combination with a storage battery cover having a hole therethrough, of a terminal post secured in said hole and having means to limit its movement axially through said hole in one direction, and means for

limiting the movement of said post through said hole in the opposite axial direction, such last mentioned means comprising a 50 partially-severed outwardly-bent portion of the post bearing against said cover.

6. The method of securing a battery terminal post in a hole in a battery cover that comprises inserting said post in said hole 55 with a part thereof projecting above the upper side of said cover, partially severing a portion of said post adjacent the upper side of said cover and pressing such partially-severed portion outwardly to form enlargement means on the post for retaining 60 the same in place.

7. The method of securing storage battery terminal posts in openings in a battery cover that comprises inserting said posts in 65 said openings with parts thereof projecting above the upper side of such cover, cutting into said posts below their upper ends and pressing outwardly integral portions of said posts to form enlargements thereon for retaining 70 said posts in place.

8. The combination with a storage battery cover having a hole therethrough, of a terminal post secured in said hole and having means to limit its movement axially through 75 said hole in one direction, and means comprising a partially-severed outwardly-extending portion of said post for limiting the movement of said post through said hole in the opposite direction. 80

9. The combination with a storage battery cover having openings therethrough, of storage battery terminal posts secured in said openings having means to limit their movement through said openings in one direction, and means comprising partially-severed outwardly-extending integral portions of said posts for limiting the movement of 85 said posts through said openings in the opposite direction. 90

In testimony whereof, I hereunto affix my signature.

C. W. HAZELETT.
